UNITED STATES PATENT OFFICE.

ERNST H. LOHRMANN, OF PROVIDENCE, RHODE ISLAND, ASSIGNOR TO WIGHTMAN & HOUGH COMPANY, A CORPORATION OF RHODE ISLAND.

DESIGN FOR A LOCKET.

No. 39,246.

Specification for Design.

Patented April 7, 1908.

Application filed January 25, 1908. Serial No. 412,678. Term of patent 3½ years.

To all whom it may concern:

Be it known that I, ERNST H. LOHRMANN, a citizen of the United States, residing at Providence, in the county of Providence and State of Rhode Island, have invented a certain new, original, and ornamental Design for a Locket, of which the following is a specification.

The figure is a plan view of a locket showing my new design.

I claim,
The ornamental design for a locket as shown.

ERNST H. LOHRMANN.
